[57] ABSTRACT

A method and apparatus is provided for catching and extinguishing burning particles so that they may be retrieved for study. A receptacle filled with inert powder is placed within the realm of falling particles and the inert powder fluidized, for example, by sublimating cubes of dry ice placed under the powder.

INCENDIARY CAPTURE DEVICE

BACKGROUND OF THE INVENTION

The effectiveness of incendiary weapons depends on the distribution and condition of the hot, burning particles arriving at a target. In some cases, notably white phosphorus, the particles or fragments are mostly in a molten state (or at least very soft) after absorbing heat from surface combustion during their trajectory. Upon impact, the hot particles or droplets spatter into much smaller pieces, which are either lost or completely burned up before recovery. It is then practically impossible to study the size distribution and character of the particles so that this can be related to target damage potential.

Considerable effort has been made in the past to find a suitable medium to capture burning white phosphorus particles from shells and grenades. Various detergent solutions, foams, and soft fibrous beds were tried without success. It is also necessary to quench and prevent further burning immediately upon capture, and this requirement may have prevented successful employment of some of the candidate media. Some success has been reported with an indirect method consisting of catching the white phosphorus particles on wet sand. The particles spatter upon impact, of course, producing star-burst patterns on the wet sand. It is, therefore, necessary to have a calibration of star-burst size versus known white phosphorus particle sizes in order to evaluate the star-bursts obtained from this method. However, no knowledge was gained in such tests as to particle shape and condition or what proportion was yet unburned.

In addition to the requirements of softness of the recovery bed, practically zero surface tension, ability to cool the incendiary particle rapidly and prevent further oxidation, there is also the necessity for a low-cost and simple system. As many as 24 catching devices may be arrayed around the shell burst point. These must be serviced and the product removed rapidly after each test.

According to the present invention, incendiary particles are captured in a fluidized bed of inert non-wettable powder. The powder is fluidized by placing readily obtainable dry ice under the powder in sufficient quantity to keep the bed of power fluidized by the gas produced by sublimation of the dry ice. The apparent density of the fluidized bed can be adjusted by regulating the quantity and block size of the dry ice used and incendiary particles are easily recoverable from the device.

BRIEF DESCRIPTION OF THE SEVERAL VIEWS OF THE DRAWING

FIG. 1 is a schematic cross sectional view of an incendiary particle capture device according to the invention;

FIG. 2 is a graph of test results when test arrows were dropped into a particular capture device according to the invention; and

FIG. 3 is a graph of the energy absorbed by the penetration of the arrows.

Shown in FIG. 1 is a form of incendiary capture device 10 according to the invention which utilizes a container 11 which may be an ordinary pail or bucket. In the container 11 is hung a basket 12 by means of handles 13 resting on the upper rim. The basket frame 12

supports a screen bottom 14 with mesh fine enough to retain the smallest particle practically useful to retrieve. In this instance layers of chunks of dry ice 15 are shown in the bottom of the container and a second layer of dry ice in the basket. The remainder of the space in the container is nearly filled with a non-wettable inert powder 16. In the device shown in FIG. 1, the powder is indicated as being essentially potassium bicarbonate (KHCO_3) although any of a number of inert powders may be used. It is also desirable that the powder be insoluble and non-wettable.

A conveniently available and highly suitable powder was found to be a fire extinguisher powder consisting of KHCO_3 finely ground and treated with a silicone compound to make it insoluble and non-wettable. This powder popularly known as Purple K is a U.S. Government stock item supplied by Chemical Concentrates Corporation, Fort Washington, PA, to MIL-F-222-87A* in 50 lb. steel buckets. These buckets were found to make excellent containers for the purposes of this invention.

* 92 percent by weight KHCO_3 0.2 max moisture; remainder silicone waterproofing and anti-caking ingredients.

This arrangement provides a soft cool extinguishing bed of fluidized powder to catch incendiary particles for study.

ANALYSIS

In the beginning it was established as general guidelines that particle sizes of one-eighth, one-fourth and one-half ml by volume were to be expected and that they might have fallen from a maximum height of 100 ft. From this the maximum energy to be absorbed by a capture medium was calculated by the following procedure:

The kinetic energy of the falling WP particle is given by

$$KE = (\frac{1}{2}) MV^2 \quad (1)$$

and in turn the velocity, V , at the end of 100-ft fall is given by

$$V^2 = V_T^2(1 - e^{-(2gS/V_T^2)}) \quad (2)$$

where

V_T = terminal velocity

S = cross-sectional area of the particle

At terminal velocity, weight = drag, hence

$$W = D = (\frac{1}{2}) \rho V_T^2 SC_D \quad (3)$$

where

ρ = air density, slug/ft³

C_D = drag coefficient, 0.47**

** "Fluid-Dynamic Drag," by S. F. Hoerner, 1965, pp. 3-8.

$$V_T = \sqrt{(2 \times 0.00203)/0.47 \times 0.000817 \times 0.002378} = 66.6 \text{ ft/sec}$$

Therefore, from Eq. 2,

$$V^2 = (66.6)^2(1 - e^{-1.445}) = 3,400$$

and

$$V = 58.4 \text{ ft/sec}$$

The kinetic energy then is

$$KE = \frac{1}{2} \times 0.00203/32.2 \times (58.4)^2 = 0.1071 \text{ ft-lb.}$$

This kinetic energy must be absorbed within a reasonable depth of penetration into the capture medium. The next step, therefore, is to measure the energy absorption by penetration. For this purpose the incendiary particles were simulated by arrows in which the tips were styrofoam balls of one-eighth, one-fourth, or one-half ml volume, the shafts were balsa wood, and instead of feathers, paper fins were used at the rear for stability. The shafts and fins were tailored so that the total weight of the arrows divided by the volume of the styrofoam balls gave an apparent density equal to that of solid white phosphorus—namely, about 1.85. A notch was cut at the back of each shaft so that gram weights could be hung by fine threads for the static penetration tests.

The penetration data were obtained by noting the depth of penetration for various loads on the arrow. By measuring the area under the resulting curves of penetration depth versus load and replotted it as energy absorbed versus penetration depth, one can then readily determine penetration depth for any kinetic energy. The use of such an arrow for these tests made it convenient to measure penetration into an opaque medium.

Five pounds of dry ice in blocks averaging about $2 \times 3 \times 1$ inches were placed in the bottom of a Purple K bucket, evenly scattered, and 45 pounds of Purple K powder were slowly shoveled on top of the dry ice. The apparent volume increased about 25 percent due to the boiling or fluidizing action. Gram weights were hung on two arrows, one with a $\frac{1}{2}$ -ml cube and the other with a $\frac{1}{2}$ -ml sphere of styrofoam, to obtain load versus penetration curves as shown in FIG. 2. These were replotted as energy absorbed (area under the curves) versus penetration (FIG. 3). As noted earlier, a value of 0.1071 ft-lb or 1,480 g-cm was obtained for a $\frac{1}{2}$ -ml particle falling 100 ft. This exceeds the range of the curves of FIG. 2, but an extrapolation gives a penetration depth of 34 cm or 13.4 inches, therefore, the 15-inch-deep bucket of Purple K would be sufficient.

A drop penetration test was made to check the validity of these calculations. It was difficult to arrange a 100-ft drop test, so the drops were made from a height of 11.2 ft, for which it was calculated the $\frac{1}{2}$ -ml cube should penetrate 7.5 inches. A total of 6 drops were made, averaging 7.2 inches penetration, which was considered a reasonably good check.

CONCLUSION

This capture device avoids the thermal shock of liquid-quenching of burning particles and also the forces of surface impact. It also provides a protective medium until retrieval. A fluidized bed is produced without resort to mechanical pumps or cylinders or compressed gas; the apparatus is extremely simple and inexpensive.

The fluidized bed can be produced by piping in any other desired inert gas, or by using other frozen gases

which vaporized directly from the solid. Any other suitable inert powder compatible with the incendiary materials may be used.

Particles caught in the beds of powder are retrieved by lifting the basket and washing away any powder clinging to the particles. Maintaining some dry ice on the screen aids in moving the basket through the powder and fluidization may be continued indefinitely by addition of dry ice above and below the screen while tests are being conducted.

The non-wettability property of the Purple K powder used makes it easy to flush the powder away from the retrieved particles.

What is claimed is:

1. A method of investigating the effectiveness of incendiary weapons including:
  - 1. placing a plurality of containers in spaced relationship in an area surrounding a weapon to be tested;
  - 2. creating a fluidized bed of inert powder in each container;
  - 3. activating the test weapon; and
  - 4. examining any incendiary particles falling into said fluidized beds.
2. The method of claim 1 wherein said powder is treated to be non-wettable.
3. The method of claim 1 wherein the powder comprises potassium bicarbonate treated to be non-wettable.
4. The method of claim 3 wherein said powder is fluidized by sublimation of solidified carbon dioxide.
5. The method of claim 1 wherein said powder is fluidized by sublimation of solidified carbon dioxide.
6. Apparatus for catching and retrieving incendiary particles comprising:
  - a container;
  - a quantity of inert non-wettable powder in said container;
  - means associated with said container for causing said powder to assume a state of fluidization; and
  - means for separating and removing from said powder particles of incendiary matter entering said container.
7. Apparatus according to claim 6 wherein said powder consists essentially of potassium bicarbonate.
8. Apparatus according to claim 6 wherein said means for fluidization comprises solidified carbon dioxide.
9. Apparatus according to claim 6 including a basket fitted in said container and having a metal screen bottom and handles extending outside said container.
10. Apparatus according to claim 6 wherein said powder consists essentially of potassium bicarbonate treated to be nonwettable;
  - 1. said means for fluidization comprises solidified carbon dioxide; and
  - 2. a basket fitted in said container and having a metal screen bottom and handles extending outside said container.
